UNITED STATES PATENT OFFICE

JACOB ROBERT WOLF, OF PITTSBURGH, PENNSYLVANIA, ASSIGNOR TO SMART SET SHOPS, OF PITTSBURGH, PENNSYLVANIA, A CORPORATION OF PENNSYLVANIA

DESIGN FOR A STORE

Application filed October 26, 1929. Serial No. 33,169. Term of patent 3½ years.

To all whom it may concern:

Be it known that I, JACOB ROBERT WOLF, a citizen of the United States, residing at Pittsburgh, in the county of Allegheny and State of Pennsylvania, have invented a new, original, and ornamental Design for Store, of which the following is a specification, reference being had to the accompanying drawings, forming part thereof, in which:

Fig. 1, showing the dominant feature of the design, is a fragmentary view in perspective elevation of the rear portion of a store interior, showing my new design.

Fig. 2 is a diagrammatic view in front elevation of the store.

Fig. 3 is a plan view or horizontal section on the line III—III of Fig. 2, showing the outline of the interior construction embodying the design.

I claim:

The ornamental design for a store, as shown and described.

J. ROBERT WOLF.
